INVENTOR, BY
Buford Tracy & Osgood
Attns. Buffalo
N.Y.

UNITED STATES PATENT OFFICE.

CHILION M. FARRAR, OF BUFFALO, NEW YORK.

DESIGN FOR STEAM-ENGINES.

Specification forming part of Design No. 5,776, dated April 16, 1872.

Specification describing a Design for "Steam-Engines," invented by CHILION M. FARRAR, of Buffalo, in the county of Erie and State of New York.

The nature of my design is fully represented in the accompanying drawing, in which—

Figure 1 is a side elevation. Fig. 2 is a plan view; Fig. 3, a front, and Fig. 4 a rear elevation.

My invention is an improvement or variation on a design patent granted me August 1, 1871, No. 5,146; and the present improvement consists in placing the steam-chest and valves A above the cylinder B instead of below, as in the former patent, while the exhaust is discharged through the jackets a a', which run around the outside of the cylinder in the usual

manner, and exits beneath at b, as clearly shown and described. The other features are similar to the first patent and need not be described.

Claim.

What I claim as my invention is—

The design of the engine as a whole, when having the steam-chest and valves above the cylinder, as clearly shown in the accompanying drawing.

In witness whereof I have hereunto signed my name in the presence of two subscribing witnesses.

CHILION M. FARRAR.

Witnesses:

J. R. DRAKE,
C. N. WOODWARD.
